[57] **CLAIM**

The ornamental design for a corner connector for furniture panels, substantially as shown and described.

DESCRIPTION

FIG. 1 is an end elevation of a corner connector for furniture panels embodying our new design and showing the cross-sectional shape thereof;

FIG. 2 is a side elevation of the corner connector for furniture panels shown in FIG. 1; and

FIG. 3 is a perspective view of the corner connector for furniture panels shown in FIG. 1.

FIG. 2 is shown broken away at the center to indicate indeterminate length.

Fig. 2
